SPIRALED CONVEYOR CART FOR USE
PRIMARILY IN SUPERMARKETS

Malcolm E. Musser, Jackson Center, Ohio 45334

Filed June 7, 1967, Ser. No. 7,391

Term of patent 14 years

Int. Cl. D12—02

U.S. Cl. D33—14

I claim:

The ornamental design for a spiraled conveyor cart for use primarily in supermarkets, substantially as shown.
